Hedges.

UNITED STATES PATENT OFFICE.

MATTHEW M. MERRITT, OF DANVERS, MASSACHUSETTS. ASSIGNOR TO COPPER PRODUCTS COMPANY, OF BOSTON, MASSACHUSETTS. A CORPORATION OF MAINE.

SHOE LAST.

1,282,258.

Specification of Letters Patent.

Patented Oct. 22, 1918.

Application filed December 3, 1915. Serial No. 64,907.

To all whom it may concern:

Be it known that I, MATTHEW M. MERRITT, a citizen of the United States, and a resident of Danvers, county of Essex, Commonwealth of Massachusetts, (whose post-office address is Danvers, Massachusetts,) have invented an Improvement in Shoe-Lasts, of which the following description, in connection with the accompanying drawings, is a specification, like characters on the drawings representing like parts.

This invention relates to metal surfaced articles wherein the core or body of the article is composed of some non-metallic substance, such as wood or the like, employed to give shape to the article, while the surface thereof is composed of a protective layer of closely adhering metal following accurately the contour of the core. The invention has a great variety of uses, but as a specific application thereof I have described it as applied to a shoe last intended more particularly for use in the manufacture of rubber boots or shoes. While this is merely one specific embodiment of the invention, the service to which a last of that kind is put well illustrates some of the advantages following its use.

It has been found in practice that a material, such for example as wood, which can be turned down in a shaping machine and thereby accurately and economically shaped to take the exact form required for a rubber shoe last, is the most suitable material for that purpose. Wood has heretofore been the material generally used despite certain well recognized disadvantages. One disadvantage is the porosity of the wood and its tendency alternately to swell and shrink when subjected to changes in temperature and moisture. This characteristic has necessitated the use for rubber shoe lasts of the more expensive and harder kinds of wood, and even this material must be subjected to a long process of preparation prior to forming it into lasts, such process involving seasoning the wood for a period of from three to four years and then heating or baking it for a further long period. Even with these precautions the heat and moisture to which the wooden lasts are subjected in the process of rubber shoe manufacture is such that they tend to undergo wide variations in size owing to shrinkage or swelling at different

times. The process of preparing these wooden lasts is expensive in that it required the investment of considerable capital in a non-productive state for a long period of time. These wooden lasts when completed are easily destructible, the edges and sharp contours tending to wear down, due to a charring process, and the surface being readily dented and splintered as well as abraded where the edges of the shoe are trimmed on the last. When worn out the lasts are waste product having no reclaiming value.

Efforts have been made to produce a metallic last by casting the last in a mold, but these have been accompanied with certain disadvantages. Shrinkage and other imperfections which are inherent in this method of manufacture not only produce defective lasts, but, what is of greater importance, cause non-uniformity in the product and discrepancies in size and shape from the intended form as embodied in the wooden pattern used in forming the mold. The last produced by this process is furthermore expensive and the limitations of the process are such that for the economical production of the lasts there is considerable delay in their manufacture. This is a serious disadvantage where rapidly changing styles are concerned.

I have found that by taking a base of wood or other suitable or similar material and applying thereto a surface of metal following the contour of the wooden base, I am enabled to produce a last which has all the advantages of the accurate and easily produced contour of the wooden last and also in substance, the durability and unchanging characteristics and unalterability of the metallic last when subjected to the severe conditions of rubber shoe manufacture. Preferably, though not necessarily, the metallic coating entirely covers the wooden form so that it provides a closely adherent, hermetic seal for the entire surface of the wood. It thereby results that the latter is not exposed to changes of moisture and heat or to the extremities of heat that an all wooden last is, and it is unnecessary to prepare the wood with the same degree of care as in the case of an all wooden last, but, on the contrary, a relatively softer and lighter and more porous wood and a relatively greener wood may be employed without the long exposure to the seasoning and drying process referred to

thereby not only lessening the expense of the wooden form, but expediting the manufacture.

Preferably I form a metallic coating upon the wooden base by electrolytically depositing metal thereon. This provides a coating of any desired thickness or thinness entirely covering the wooden surface closely adherent to the wood and following accurately all 10 the irregularities in the surface thereof.

The electrolytically deposited copper has a relatively great density and hardness so that it is well adapted to resist denting and scratching. It is also susceptible of taking 15 a high polish, thus reducing the wear on the edges and other portions where the wooden last is most susceptible of wear. The knots, seams and other imperfections in the wood may be completely covered and protected 20 by the electrolytically deposited coating, thereby making it possible to employ wood for this purpose not otherwise usable. I am thus enabled to avail of the superiority of wood as a material capable of being accurately, economically and quickly shaped, 25 while its usual disadvantages are eliminated by its combination with the metallic coating.

The invention will be best understood by reference to the following description when 30 taken in connection with the accompanying illustration of one specific embodiment thereof, while its scope will be more particularly pointed out in the appended claims.

In the drawings:

35 Figure 1 is a sectional elevation of a last embodying one form of the invention;

Fig. 2 is a sectional view partly diagrammatic in character showing the method of 40 depositing the metal surface on the wooden form; and

Fig. 3 is a detail showing the method of securing the electrodes to the last during the process of depositing the metal thereon.

Referring to the drawings and first to 45 Fig. 1, I have there illustrated a last of a form intended for use in rubber shoe manufacture. This last is composed of the wooden core 1 of a predetermined size and shape, the shape and size of cores varying 50 with the infinite variety of patterns required. This wooden base is turned down to the required size on the usual shaping machine, allowance being made, if desired, for the increased thickness due to the subsequently applied surface of metal.

Covering the wooden base, and herein for its entire surface, is a protective layer of metal 2, composed of electrolytically deposited metal, herein copper, forming a 60 closely adhering jacket following the exact shape and contour of the wooden core and exhibiting all the characteristics of the form thereof. The thickness of the copper covering may be varied to meet different conditions of use as it is only necessary to in-

crease the time of exposure to the electrolytic bath or the current density to increase the thickness of the coating. In the form of last shown in the drawings, the copper covering is approximately one sixty-fourth 70 of an inch in thickness, but it may be made thinner or increased to any desired extent. In the case of a last, however, it is desirable to keep within such limits as will insure a close correspondence by the metallic surface 75 to the exact contour of the form. The electrolytic deposit may be applied in any well known way and by means of any well known copper bath.

In Fig. 2 I have represented at 3 a tank 80 containing the electrolyte 4 and the anodes 5 and 6 between which is immersed the last or other form 7. Prior to immersion the last is first preferably coated with some suitable water-proofing material such as 85 shellac or paraffin or water glass to prevent the absorption of moisture from the electrolyte, and is then covered with a thin, conductive coating of suitable conductive material such as graphite which can be 90 readily brushed over the wooden surface to produce a conductive surface on which to deposit the metal.

In order to provide for a uniform deposition of the metal upon the form, I make 95 use of conductors having surface contact with the form and insulated from the bath. As a convenient method of fastening the terminals of these conductors to the last and holding the latter in suspension, I have pro-

vided one or more plugs 8 of lead or other suitable material, the same being embedded in the last flush with the top thereof and bored to provide the spindle holes 9, which later can be utilized to support the last in 100

the process of shoe manufacture. Inserted in the spindle holes 9 are the conductor terminals 10, exposed portions of which are insulated at 11. These are electrically connected by the screws 12, also insulated from 105

the electrolyte, to the conductor 13, which latter passes through the hollow insulating material to any suitable current source exterior to the tank. After the deposition has been completed, the last is removed from the 110 tank and the terminals 10 withdrawn, leaving the last covered uniformly with the copper covering except at the spindle holes 9. The lead plugs 8 serve to seal the wood 115 of the last at the spindle holes which would otherwise be unprotected and at the same time serve as a convenient means for securing a surface contact between the electric conductors and the conductive coating on 120 the last so that the deposition tends to take place evenly throughout the surface thereof.

The lead plugs or inserts 8 not only provide means for securing an internal, protected contact between the circuit terminal or terminals 10 and the conductive surface 125 130

applied to the last, but they also constitute reinforcements of relatively better wear-resisting material than the wood for that part of the wooden core which it is necessary 5 to socket upon the spindle supports. In the case of articles where greater wear-resisting qualities are required than are afforded by lead, the wood or other material of the core may be reinforced by steel, brass or any 10 other desired material applied to the core or base in the form of an insert, or in any other desired manner. Such reinforcement, however, can be applied as in the last illustrated in the drawings, so that it both seals 15 and protects the material of the core to which it is applied and also permits the covering of metal to be deposited over any exposed portions of the reinforcement itself, leaving a perfectly smooth, seamless cov- 20 ering.

The last produced by the process described consists of the wooden form covered entirely by a dense, hard, thin layer of copper which is susceptible to a high polish and which fol- 25 lows the exact configuration of the wooden core as to all details, bringing out all edges and curves in sharp definition and with exact fidelity. The presence of roughness, pores or other small irregularities in the sur- 30 face not only form no detriment to the deposition of metal on the surface of the core, but actually assist in causing a firmer and inseparable adherence of the metallic coating to the surface of the core, which adher- 35 ence, however, is naturally such as to prevent the separation of the coating from the core through any ordinary conditions of wear or usage. The wood being protected by the metallic coating is not susceptible 40 to shrinking and swelling as is the unprotected last of wood and the durability of the last is greatly increased.

It will be understood that while I have

herein described for purposes of illustration one specific form of the invention, the same 45 is not limited to the exact details herein set forth or the particular use or application made thereof, but that extensive deviations may be made therefrom without departing 50 from the spirit thereof.

Claims:

1. A rubber shoe last having a wooden core and a metallic surface entirely inclosing the same and one or more metallic inserts in the head of the last, said insert or inserts 55 being bored to provide a spindle hole or holes.

2. A shoe last provided with a core or body of a material having relatively low wear-resisting qualities, one or more metallic inserts in the head of the last, said insert or inserts being bored to provide a spindle hole or holes, and a hard protective layer of electrolytically deposited metal covering the exposed surface of said last. 60

3. A shoe last having one or more metallic inserts in the head of the last, said insert or inserts being bored to provide a spindle hole or holes, and a hard shell of electrolytically deposited metal forming the surface of the 70 last and joining said insert or inserts in the head of the last.

4. A last having a metal reinforcing piece at the top thereof and an electrolytically deposited shell, said reinforcing piece providing an inwardly extending projection engaging the form on which said shell was electrolytically deposited. 75

In testimony whereof I have signed my name to this specification in the presence 80 of two subscribing witnesses.
